[57] CLAIM

The ornamental design for a lip gloss compact, as shown.

DESCRIPTION

FIG. 1 is a side elevation of a lip stick compact showing my new design;

FIG. 2 is an elevational view of the opposite side;

FIG. 3 is a top plan view thereof, the bottom view being a mirror image;

FIG. 4 is an end elevation from the left of FIG. 1;

FIG. 5 is an end elevation taken from the right of FIG. 1, in an opened condition; and

FIG. 6 is a perspective view thereof.
